SHELL TYPE SLUICE GATE

César Jimenez Lopez, Mexico, D. F., Mexico

Application January 18, 1938, Serial No. 185,598
In Mexico December 10, 1937

3 Claims. (Cl. 61—22)

The present invention relates to sluice gates for dams in general, and it more particularly concerns a sluice gate of improved constructions, different from the ones known at this time because the form of the frontal surface permits the latter to perform a leading function in the resistance borne against it by the pressure of water, thus allowing the sluice gate to be lighter, its shape being entirely different from that of other sluice gates existing at the present time.

The term "shell type sluice gate" comes from other structures previously called, the principles of the design of which is applied to such other sluice gates.

15 The sluice gate can be built using one or several shells, which are structures having three continuous, thin dimensions, and having a surface engendered by a curved directrix and a straight or curved generatrix.

20 The shell can be of the open or closed type. The shell type structure is characterized by its ends being embedded or secured to rigid guides, in both types, and in the case of open shell forms, their longitudinal edges are tied to girders or bars the principal object of which is to lend rigidity to the structure, whereas in the ordinary sluice gates, the girders or bars have as their only function that of the transmission of the loads to the supports of the sluice gate.

25 In the structure of the closed shells, the rigid longitudinal girders disappear, because the function of the latter is automatically performed by the closing of the structure which forms tubes that may be of a circular or elliptical section or any other closed curve in which there can be applied the same principle that serves as the basis for the shell type sluice gate.

30 The excellent structural properties of the closed shell forms are due to the fact that the external pressures on the surface are transmitted, in large part, by direct, longitudinal stress, with the shell form operating as a girder of cylindrical section, embedded in its rigid frames.

35 In the open shell forms the rigid or boundary girders, which run longitudinally following along the edge of the shell form, prevent the occurrence of large deformations on the edges, and the action of the whole from the structural point of view is similar to the case of the closed shell forms.

40 The characteristic details of this new sluice gate, are clearly shown in the following description and in the attached drawings.

45 Figure 1 is a conventional perspective view of a shell type sluice gate, the water-tight closure, bearing and elevating systems being omitted to clearly represent the features which constitute the present invention.

50 Fig. 2 is a perspective view of a modified form of sluice gate.

The illustrated sluice gate consists of shell like sections *a*, *b*, *c*, the last one of which is that of the bottom and which are of cylindrical, circular, and open form, having different thicknesses and radius of curvature.

5 The rigid or boundary girders or bars *f*, *g*, *h*, *i*, are also different from one another and have been drawn in I section, and may be of box type or any other kind of section.

The end frames comprise rectangle plates to which the shell sections and the girders are 10 closely tied.

To illustrate the drawings more clearly, a section parallel to the frames that includes the two upper shell sections *a*, *b* and part of the lower one *c*, is shown, and in it can be seen the location 15 of the longitudinal girders or bars. The part of the frame which is not shown because of the location of the section is represented by dotted or broken lines.

20 The system operates by receiving the pressure of the water on the convex part of the shell sections indicated by the arrow *F*.

Figure 2 represents a somewhat different form of sluice gate of shell construction and comprises shell sections *a'*, *b'* and *c'* shown cylindrical and 25 hollow, but may be oval in cross section.

The frames *d'* and *e'* perform the same function as the form shown in Figure 1.

20 The upper shell sections *a'* and *b'* and part of the lower shell section *c'* are shown in section for 30 the purpose of giving a better idea of the structure.

Having thus described the invention, what I consider as new and desire to secure by Letters Patent is:

35 1. A sluice gate comprising side members, and a series of contacting shell-like horizontal members having curved outer surfaces and connected to the side members, the vertical depth of the shell-like horizontal members varying from the 40 bottom member to the top member, the lower member being the largest.

2. A sluice gate comprising side members, a series of horizontal cross members connected to the side members, said horizontal members being 45 open at their rear and curved on their front, a series of bars inside each horizontal member where said horizontal members abut, and bars at the inner terminals of said horizontal members, all said bars being connected with the side members.

3. A sluice gate comprising side members, a series of shell-like horizontal members open at their rear and having their front surfaces convex, the vertical depth of the shell-like members 55 varying from the bottom member to the top member, the lower member being the largest.

CÉSAR JIMENEZ LOPEZ.
